UNITED STATES PATENT OFFICE

2,010,198

DRAFTING APPLIANCE

Henry W. Rice, East Boothbay, Maine

Application December 11, 1933, Serial No. 701,908

1 Claim. (Cl. 33—104)

This invention relates to an appliance or accessory characterized by two or more drawing instruments and a carrier or holder therefor, the entire device being especially, but not necessarily, adapted for use by school children and being expressly designed to be conveniently fastened in a loose leaf binder, notebook or the like.

Briefly stated, the inventive conception comprehends an assembly of parts, the main part of which serves as a pattern or guide to aid in drawing and measuring, and has the additional function of a holder or carrier for detachable accessories, for example, a triangle, and an irregular curve or the like.

When constructed in accordance with the principles of the present invention the structure, as a unit, is stamped out from sheet material of appropriate texture to form the main pattern and said main pattern is in turn stamped out to provide, within itself, additional instruments for selective use, the idea being to provide a simple, economical and useful appliance serving as a guide to facilitate the drawing of geometrical figures, astronomical designs and the like.

Other features and advantages will become more readily apparent from the following description and drawing.

In the drawing:

Figure 1 is a top plan view of a device constructed in accordance with the principles of the present inventive conception.

Figure 2 is an edge elevational view thereof.

Figure 3 is an enlarged detail section taken approximately on the plane of the line 3—3 of Figure 1.

Figure 4 is a view like Figure 3 showing the retaining button moved to releasing position.

Figure 5 is a detail view of the retaining button per se.

Figure 6 is a fragmentary view of an edge portion of the main pattern or holder.

By way of introduction it is to be stated that the invention may be constructed of any appropriate texture or character of sheet material.

For example it can be inexpensively made from cardboard, from hard rubber, aluminum or the like but it is preferably made from some substantially translucent composition such as is used in the construction of regulation patterns and guides used by draftsmen.

The main pattern, which is in itself a guide is denoted in Figure 1 by the numeral 9. It is of general rectangular form and along the longitudinal edge 10 slots 11 are formed, the slots being appropriately spaced so as to permit this part to

be clasped or held in the snap rings of a loose leaf binder or notebook such as is used by school children and students. The opposite longitudinal edge 12 is preferably formed with graduations 13 so that it may be used as a straight-edge and ruler. One end 14 is shaped to provide the curve of a predetermined shape to function as a pencil guiding edge. The opposite end portion 15 is also of suitable configuration so that it may be used as an aid and guide in the drawing of predetermined lines.

As before stated, this main pattern or part 9 is formed within itself with supplemental instruments or parts, one of which is distinguished by the numeral 16 and the other one by the numeral 17. The detail 16 may be described as a triangle and the detail 17 as an irregular curve. These parts 16 and 17 are struck out from the body of the main part or pattern 9. It is to be pointed out that the material possesses inherent resiliency and when the parts 16 and 17 are struck out they do not readily snap back into place when replaced. To compensate for this it will be observed that substantially circular holes 18 and 19 are formed at the apex ends of the openings from which the parts 16 and 17 are struck out and this provides for requisite expansion and contraction to facilitate application and removal of said parts 16 and 17.

Referring to the part 17, it will be observed that it is provided with a plurality of apertures of appropriate shape and dimension to function as guides and to aid in the drawing of certain designs and figures. For example the numeral 20 designates a diamond cut out, 21 a star, and 22 a crescent. It is understood, of course, that these openings may be of any predetermined formation, this being an incidental feature of the invention.

As a safety measure, where the material is lacking in resilient property, and where the parts 16 and 17 would become easily displaced from their receptive openings I have found it advantageous to provide slidable retaining buttons. These buttons are all of the same kind and they are distinguished by the numerals 23 wherever they occur. The buttons are of suitable material and as shown in Figure 5 each button comprises a shank 24 formed with disk like heads 25 which have frictional sliding contact with the upper and lower surfaces of the parts with which they co-operate. These buttons are slidably mounted in special apertures provided therefor as shown in the drawing. It might be mentioned, however, that the openings 18 and 19 which serve as ex-

pansion means may also serve to accommodate these buttons 23. At other points where the buttons are used, that is around the marginal portions of the opening from which the parts 16 5 and 17 are struck, the apertures are of keyhole shaped form and denoted by the numerals 26, shown for example in Figure 6. When the buttons are released they are slid out into the enlarged portions of the slots 26 and when adjusted to retaining position are adjusted into the restricted or neck portions of the slots. When in the latter portions of the slots the disk like heads 25 overlap adjacent portions of the parts 9, 16 and 17 with which they cooperate as shown 10 in Figure 1. Some idea of the manner of adjusting the button from retaining to release position is illustrated in Figures 3 and 4.

The principal novelty is predicated upon a body of sheet material of appropriate nature 20 characterized by a main pattern from which supplemental patterns are struck out, whereby to provide a plurality of individual instruments susceptible of selective use. The idea of constructing the part 9 to serve as a carrier and holder 25 for the parts 16 and 17 is unique. Secondly, the idea of providing this part 9 with slots 11 so that it may be fastened in snap rings or the like in a loose leaf binder is advantageous in a school appliance of this kind. In the most simple and economical type of the device recommended for 30 the trade the adjustable button fastener 23 may be omitted, since the parts 16 and 17 are more or less self retaining when the material from which

said parts are made is of suitable resilient nature. When however, the buttons are used it is obvious that the shank portions of the button are slidably mounted in slots arranged around the marginal portions of the opening from which the parts 16 5 and 17 are pushed out when desired for use.

A careful consideration of the foregoing description in conjunction with the illustrative drawing will enable the reader to obtain a clear understanding of the purpose, features and advantages, the explicit construction, and the invention as hereinafter claimed. 10

It is to be understood that minor changes in shape, size, relative proportions, and materials may be resorted to in practice without departing 15 from the spirit of the invention or the scope of the invention as claimed.

Having thus described my invention, what I claim as new is:

An appliance of the class described comprising 20 a body, said body being constructed of sheet material, an individual drawing instrument struck out from said material, said instrument fitting removably in the opening from which it is struck when not in use, and there being slots formed 25 around the edge portions of said last named opening, and a group of slidable fasteners, each including a pair of buttons on the ends of a shank, the shanks being slidable in the slots, and the buttons cooperating with the edge portion of said 30 instrument to aid in holding the instrument in place when not in use.
